UNITED STATES PATENT OFFICE.

GEORGE S. VAN PELT, OF NEW YORK, N. Y., ASSIGNOR TO WILLIAM C. HOWARD, OF SAME PLACE.

DESIGN FOR A FOUNTAIN-SYRINGE BAG.

SPECIFICATION forming part of Design No. 33,216, dated September 18, 1900.

Application filed July 17, 1900. Serial No. 23,978. Term of patent 14 years.

To all whom it may concern.

Be it known that I, GEORGE S. VAN PELT, a citizen of the United States, residing at New York, borough of Manhattan, county and State of New York, have invented and produced a certain new and original Design for Fountain-Syringe Bags, fully described and represented in the following specification and the accompanying drawing, forming a part of the same.

10 This invention relates to a new and original design for bags; and the invention consists in a peculiar shape or configuration of the same, substantially as shown in the accompanying drawing.

15 The leading feature of the design is the pe-

culiar shape of the body of the syringe-bag below the widest part A, below which it is formed with the inward curves *a* and extended narrower portion B, having substantially straight sides *b*.

What I claim is—

The design for a fountain-syringe bag, substantially as shown and described.

In testimony whereof I have hereunto set my hand, this 12th day of July, 1900, in the presence of two subscribing witnesses.

GEORGE S. VAN PELT.

Witnesses:

C. J. SAWYER,
T. F. KEHOE.
